EYE MEASURER FOR EYELASHES

Charles Kim, 215 W. 83rd St.,
New York, N.Y. 10024

Filed Mar. 4, 1969, Ser. No. 16,019

Term of patent 14 years

Int. Cl. D10—08

U.S. Cl. D52—6

FIG. 1 is a perspective view of the eye measurer for eyelashes according to the invention;

FIG. 2 is a top view of the eye measurer of FIG. 1;

FIG. 3 is a front view of the eye measurer of FIG. 1;

FIG. 4 is a side view for the eye measurer of FIG. 1;

FIG. 5 is a rear view of the eye measurer of FIG. 1;

and

FIG. 6 is a view taken on line 6—6 of FIG. 1.

I claim:

The ornamental design for an eye measurer for eyelashes, as shown.
